C. O. HAYWARD

HOLDER DEVICE

Filed Feb. 27, 1923

UNITED STATES PATENT OFFICE.

CHARLES O. HAYWARD, OF RAVENNA, MICHIGAN.

HOLDER DEVICE.

Application filed February 27, 1923. Serial No. 621,505.

To all whom it may concern:

Be it known that I, CHARLES O. HAYWARD, citizen of the United States, residing at Ravenna, county of Muskegon, State of Michigan, have invented certain new and useful Improvements in Holder Devices, of which the following is a specification.

This invention relates to improvements in holder devices.

10 The main objects of this invention are to provide an improved holder device which may be adapted as a hat hanger or as a key-ring or holder for keys, car-checks or other articles, and one which may be engaged with 15 different parts of the garment as with the edge of a pocket or button hole, or with a button.

A further object is to provide a device having these advantages which is simple 20 and economical to manufacture and to manipulate.

Objects pertaining to details and economies of the invention will definitely appear from the detailed description to follow.

25 I accomplish the objects of my invention by the devices and means described in the following specification. The invention is clearly defined and pointed out in the claims.

A structure which is a preferred embodiment of the invention is clearly illustrated 30 in the accompanying drawing forming a part of this application, in which:

Fig. I is a perspective view of my improved holder device represented as engaged 35 with the pocket of a coat and supporting a hat.

Fig. II is an elevation of my improved holder.

Fig. III is an edge view of my improved 40 holder.

Fig. IV is a detail view showing my improved holder employed as a holder for keys and car-checks, the holder being shown open to permit the articles to be engaged or 45 removed therefrom.

Fig. V is an elevation showing my improved holder engaged with a button.

Fig. VI is a fragmentary view showing 50 another method of using my improved holder.

Similar reference characters refer to similar parts throughout all of the views.

Referring to the drawing, my improved 55 holder comprises an annular split body 1 of spring wire terminating at one end in the arm 2 which is disposed across the body pro-

jecting beyond the same and coacting therewith to provide a spring clasp which may be engaged with the edge of a pocket, in a button hole of a garment or other support. 60 The other end of the body member terminates in a laterally and outwardly offset inwardly facing hook 3 which is adapted to be passed through the bight 4 formed by the arm 2 and sprung into engagement with the opposite end, whereby the hook is held in engagement, but may be released as indicated in Fig. IV to permit the arrangement of keys thereon as 5, or car-checks indicated at 6, or other objects as may be desired. Or, 70 the hook end may be inserted through a button-hole thereby securing the holder to a garment.

In Fig. V the arm is sprung over a button as 7.

75 It will thus be seen that the device may be engaged in several positions according to the convenience of the user.

A link 8 is engaged with the body member and carries the clasp 9 which is swivelled thereto. This clasp is adapted to be engaged with a hat thereby adapting my holder as a hat holder. This is very desirable where, for instance, a coat is hung up 80 in a public place, the hat may be attached thereto, and it will be found desirable in many other circumstances.

The holder is also desirable for use of night watchmen carrying keys and in other cases where it is desired that they shall be 90 readily accessible and at the same time securely retained.

In Fig. VI, I show the clasp as engaged with the edge of the pocket 10, the holder being retained within the pocket by the 95 clasp.

Having thus described my invention what I claim as new and desire to secure by Letters Patent is:

1. In a device of the class described, the 100 combination of an annular split body member of spring material terminating at one end in an outwardly offset inwardly facing hook and at the other end in an arm disposed across the body and coacting therewith to provide a spring clasp adapted for engagement with a garment or with a button or the like, the end of said arm being turned laterally, the hook end being inserted through the bight of the arm and the hook 110 being engageable therewith under spring tension, whereby the body member may be

- opened to articles, such as keys, or for the engagement with a button-hole or the like, a link on said body member, and a clasp swivelled on said link. 30
- 5 2. A device of the class described comprising an annular split body member of spring material terminating at one end in an outwardly offset inwardly facing hook and at the other end in an arm disposed 35
- 10 across the body member and coacting therewith to provide a spring clasp adapted for engagement with a garment or with a button or the like, the end of said arm being turned laterally, the hook end being inserted 40
- 15 through the bight of the arm and the hook being engageable therewith under spring tension, whereby the body member may be opened to articles, such as keys, or for the engagement with a button-hole or the like. 45
- 20 3. A device of the class described comprising an annular split body member of spring material terminating at one end in an outwardly offset inwardly facing hook and at the other end in an arm disposed across the 50
- 25 body member and coacting therewith to provide a spring clasp adapted for engagement with a garment or with a button or the like, the hook end being inserted through the
- bight of the arm and the hook being engageable therewith under spring tension, whereby the body member may be opened to articles, such as keys, or for the engagement with a button hole or the like. 30
4. A device of the class described comprising an annular split body member of spring material terminating at one end in a hook and at the other end in an arm disposed across the body member and coacting therewith to provide a spring clasp, the hook end being adapted to be inserted through the bight of the arm and the hook detachably engaged under spring tension, a link on said body member, and a clasp swivelled on said link. 35
5. A device of the class described comprising an annular split body member of spring material terminating at one end in a hook and at the other end in an arm disposed across the body member and coacting therewith to provide a spring clasp, the hook end being adapted to be inserted through the bight of the arm and the hook detachably engaged under spring tension. 40

In witness whereof, I have hereunto set my hand and seal.

CHARLES O. HAYWARD. [L.S.]
